US0D1036826S

(12) **United States Design Patent** (10) **Patent No.:** **US D1,036,826 S**
(45) **Date of Patent:** **** Jul. 30, 2024**

(54) **SHOE**

(71) Applicant: **STARLINK TECHNOLOGY CO., LIMITED**, Hong Kong (CN)

(72) Inventor: **Jie Huang**, Singapore (SG)

(**) Term: **15 Years**

(21) Appl. No.: **29/896,143**

(22) Filed: **Jun. 29, 2023**

Related U.S. Application Data

(62) Division of application No. 29/854,992, filed on Sep. 29, 2022, now Pat. No. Des. 993,583.

(57) **CLAIM**

The ornamental design for a shoe, as shown and described.

DESCRIPTION

FIG. 1 is a perspective view of a shoe showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines and the areas within depict portions of the shoe that form no part of the claimed design. The figures include textured portions, which are designed to show a stitched fabric.

1 Claim, 8 Drawing Sheets
